TRAFFIC GUARD

Eugene V. Camp, Atlanta, Ga.

Application March 12, 1935, Serial No. 10,695

24 Claims. (Cl. 256—13.1)

This invention relates to a new and improved road guard rail for positioning along dangerous stretches of highway, curves, bridge-heads, bridges, and the like, for the purpose of absorbing the shock of impact of a vehicle that has left the road and run into said guard, said barrier tending to glide the vehicle along the face of the guard and return the vehicle to the highway, without material damage to either the vehicle or rail. Specifically, the instant invention is concerned with a highway guard rail embodying a new and improved connector element or member interposed between the rail panel proper and its supports.

Modern sheet metal, plate type, guard rails, the majority of which are constructed upon the basic principle taught by my Patent No. 1,793,673, February 24, 1931; and which consist in their fundamental conception of a strip of sheet metal extending longitudinally and wholly to one side of a series of supports, plus means for maintaining said band under longitudinal tension, have been adopted in practically every state of the Union, as well as in numerous foreign countries. High speed motor cars and an ever-growing system of super-highways have made such devices very necessary; and rails of this type have been found to be generally satisfactory, acting as they do to receive and partially nullify the impacting force of a moving vehicle, which vehicle is glided along the face of the guard and eventually brought back into the roadway with a minimum of personal and property damage.

Experience has shown that it is generally desirable to construct a guard that gives freely under moderate impact, yet which has sufficient strength and resistance to bear up under a severe blow, as from a truck or heavy bus, yielding the while, however, under such increased or sustained pressure. In view of this, certain state specifications require a guard rail that will initially yield one inch under 5000 pounds pressure, yet which will sustain a maximum pressure of more than 15,000 pounds.

An object of this invention is to provide a guard rail that will yield under force of impact, yet which, will set up an increased resistance to yielding after a certain pressure has been reached.

Another object is to provide a guard rail with a spring connector which is in effect, double-acting, said connector utilizing one element for ordinary stresses, and bringing into play a second buffer element in conjunction with said first member for coping with extraordinary impacts.

A still further object is to provide cheapness of construction in a device of the foregoing type.

Another object is to provide simplicity and efficiency of operation in such a device.

Another object is to provide a guard rail that will meet certain state specifications.

Broadly stated, the objects of the instant invention are to provide in a highway guard rail, a buffer within a buffer, said elements acting independently under certain conditions, and combining their effective action under certain other conditions.

These and other objects made apparent through-out the further progress of this specification are accomplished by means of my traffic guard, and more particularly the spring connector or buffer employed therewith, a full and complete understanding of which is made possible by reference to the drawing herein, in which:

Fig. 1 is a fragmentary view, substantially in perspective, of a section of guard rail mounted to a support by means of a connector embodying my invention.

Fig. 2 is a top plan view of the structure illustrated in Fig. 1.

Fig. 3 is a view in vertical cross-section of the structure illustrated in Fig. 2, said view being taken along the line III—III thereof.

Fig. 4 is a fragmentary front elevational view of a section of guard rail embodying my invention, illustrating a modification in the manner of mounting the metal panel to the connector elements of the composite guard rail structure.

Fig. 5 is a view in vertical cross-section of the structure illustrated in Fig. 4, said view being taken substantially along the same line as Fig. 3.

Fig. 6 is a front elevational view of an assembled section of guard rail embodying my invention, said rail being of the type suggested in Fig. 1.

Fig. 7 is a top plan view of a guard rail embodying the instant invention, in which the secondary spring is conventionally cylindrical, the structure otherwise being the same as illustrated in Figs. 1 and 2.

Like numerals indicate corresponding parts through-out the various figures of the drawing.

Referring now to the drawing, Fig. 1, my invention comprises a rail or panel 10 attached to a support 11 by means of a spring connector 12. Rail 10 may consist of a sheet metal band, or it may embody a more rigid construction; and may comprise a single panel or unit or a series of such joined end to end in a suitable manner, depending upon the requirements of a given situation. Support 11 may be conventional, and formed of

25

55

either wood, concrete, or other material, said support (or post) being properly positioned in the ground, details of construction and erection in regard to which are well known to those skilled in the road building arts.

Special attention is now directed to spring connector 12. This member is preferably formed of spring steel, and may be circular, annular, oval, curved, or any other desired shape suitable for accomplishing the purposes of the instant invention, it being contemplated, however, that the axis of 12 shall be, generally speaking, transverse to panel 10, as shown in the drawing.

Rail 10 may be joined to connector 12 in any desired manner, as by means of bolts 13 and 14 and associated nuts 13a and 14a. Disposed within connector 12 and preferably spaced from the front and side walls thereof (Fig. 2), is an inner impact resisting member 15, which element may 20 resemble 12 in general contour, and be of a corresponding height, but which is of a smaller diameter than said element. In the construction illustrated, 15 is provided with side wings 15a and 15b, although this is not strictly necessary for the purposes of the instant invention, and, as a matter of fact, the element may be in the form of a closed circle, or in any other form capable of accomplishing the purposes of my invention. It is also to be noted that while in the drawing, 30 element 15 is shown anchored adjacent the post, it may instead be fastened to rail 10 as by means of bolts 13 and 14, when conditions make such an arrangement desirable.

Member 15 may be fabricated of spring steel as 35 is 12, or be of a more rigid construction, the fundamental purpose being to provide a buffer within a yielding outside element of the nature of 12 as described herein, to perform functions contemplated by the objects of this invention as set forth 40 heretofore.

Fig. 7 illustrates an embodiment of the instant invention in which buffer element 15c is in the form of a closed circle or conventional cylinder, the structure otherwise being as suggested in 45 Figs. 1 and 2; and the operation of the device being substantially identical to that described hereafter, except, however, that when the buffer is thus formed a somewhat greater resistance to impact may exist, with a corresponding lack of 50 resiliency than when a spring having wings such as 15a and 15b is employed.

Elements 15 and 12 may be united to support 55 11 in any suitable manner, as by a bolt 16 and nut 16a. If rail 10 is of the flexible type now generally employed in the rod guard industry, it is desirable to provide means for imparting tension to said rail throughout the length thereof, such means being illustrated herein in the form of coil springs 17 and 18 (Fig. 6), although any 60 other suitable means may be employed for this purpose. If a rigid plate type of rail is used, tensioning means are not usually considered necessary.

In the structure illustrated in Figs. 4 and 5, the 65 elements are substantially similar to those already described herein, with the exception that in place of being rigidly attached to spring 12 as by bolts 13 and 14, rail 10 is mounted in sliding engagement with said connector by a clip 19, said clip 70 passing around said spring at its front-rear portion, and holding the rail in engagement with the front thereof by means of end portions 19a and 19b, this construction providing a snug and workman-like connection, but at the same time making 75 possible a sliding joint through which the rail

may travel when subjected to strain or impact, or when compensation is otherwise needed, as in the case of expansion and contraction of the rail due to changes in temperature. Such a structure further simplifies the positioning of tensioning means in the guard rail device, when rail 10 is of the non-rigid type, it only being necessary to place some such means at each end of a series of sections or panels of rail, said springs then imparting tension uniformly through-out the 10 length thereof.

In operation, my device works as follows: A vehicle striking rail 10 is glided along the face thereof, the force of the impact being partially nullified by the rail itself if it is of a flexible nature, and the impact being further taken up and reduced by the cushioning effect of spring 12, said spring acting as a buffer between the panel and the post. For the lighter impacts, spring 12 is sufficient to accomplish the full purpose for which 20 the device is intended; but in the case of a severe impact, particularly at the post itself, further resisting means are necessary, and to fulfill this need, inner impact resisting member 15 is provided. This member acts as a secondary buffer, 25 and upon 12's being compressed as by a blow, to the point where the inner outside surface thereof is brought into contact with 15, a further resistance is set up, the force of the blow now having to overcome two buffers instead of one, and 30 said resistance continuing until both elements are compressed.

For illustrative purposes I have herein referred to the impact member of my traffic guard as a metal band or panel, but it is obvious that 35 any suitable means or element, such as cable for example, may be substituted therefor without departing from the spirit and scope of the instant invention.

Thus it will be seen that I have by means of 40 my invention provided what is, in effect, two guards in one. The first furnishes a light, springy, flexible guard to take care of light blows and ordinary impacts, while the second is a heavy duty, super-buffer element capable of withstand- 45 ing severe pressure, and at the same time yieldably acting to cushion the force of even the most severe impacts.

The action of the device illustrated in Fig. 4 is substantially the same, except possibly the 50 spring tensioning means at the ends of the rails may act to take up more of the shock than in the structure illustrated in Fig. 1, in which case elements 12 and 15 will not be fully compressed until a somewhat greater pressure has been exerted against the guard than in the case of the first structure in which a sort of rolling motion may be imparted to the spring connector elements upon an impact, due to the anchoring of the rail to the connector by bolts 13 and 14, it being apparent that in such a construction the springs at the supports are more relied upon to nullify impact than in the sliding-rail device. In either form, however, the spring cushions are highly important, and they are particularly so in a 65 double-acting device such as disclosed herein, the desirability of such a structure being at once apparent to those skilled in the art.

It is further apparent that my invention is simple and positive in its action, economical to 70 manufacture, readily adaptable to a wide range of highway specification requirements, and thoroughly efficient for the purposes intended. As such, it represents a distinct advance in the industry.

While I have described a preferred form of my invention herein, and suggested certain modification thereof, it is obvious that considerable change may be made in the size, form, and structure of said device, and particularly in the shape and arrangement of elements 12 and/or 15, without departing from the scope of the appended claims, which claims are to be broadly construed.

10. I claim:

1. A highway guard rail comprising a series of supports, a sheet metal panel disposed longitudinally and entirely to one side thereof, a series of annular spring connectors uniting said panel to said supports, and secondary circular spring elements mounted within said connectors in spaced relationship to the front and sides thereof in such a manner that an initial shock is first absorbed by said connectors before said secondary elements become operative.

15. 2. A highway guard rail comprising a series of metal panels joined end to end and disposed longitudinally of a series of supports, a series of annular spring connectors disposed between said panels and said supports, secondary springs within said spring connectors and disposed in spaced relationship to the interior thereof, means joining said metal panels with said spring connectors, and means for mounting said springs 20 and connectors upon said supports.

30. 3. A highway guard rail comprising a series of metal panels joined end to end and disposed longitudinally of a series of supports, a series of annular spring connectors disposed between said panels and said supports, secondary springs within said spring connectors and disposed in spaced relationship to a portion of the interior thereof, means joining said metal panels with said spring connectors, and means for mounting said springs 35 upon said supports.

40. 4. A highway guard rail comprising a series of metal panels joined end to end and disposed longitudinally of a series of supports, a series of annular spring connectors disposed between said panels and said supports, secondary springs disposed within said spring connectors and in spaced relationship to a portion of the inner walls thereof, means for slideably mounting said metal panels upon said spring connectors, and means for supporting said springs upon said supports.

50. 5. A highway guard rail comprising a series of sheet metal panels joined end to end and disposed longitudinally of a series of supports, a series of annular spring connectors disposed between said panels and supports, secondary springs disposed within said spring connectors and in spaced relationship to a major portion of the inner walls thereof, clip means for slideably mounting said panels upon said spring connectors, and means for supporting said connectors upon said supports.

60. 6. A highway guard rail comprising a series of metal panels joined end to end and disposed longitudinally of a series of supports, a series of annular spring connectors disposed between said panels and said supports, secondary buffer members disposed within said spring connectors in such a manner that an initial shock is first absorbed by said connectors before said secondary elements become operative, means for slideably mounting said metal panels upon said spring connectors, and means for supporting said springs and connectors upon said supports.

70. 7. A highway guard rail comprising a series

of metal panels joined end to end and disposed longitudinally of a series of supports, a series of annular spring connectors disposed between said panels and said supports, secondary buffer elements disposed within said spring connectors in such a manner that an initial impact is first absorbed by said connectors before said secondary elements become operative, means joining said metal panels with said spring connectors, and means for mounting said springs and connectors 10 upon said supports.

8. A highway guard rail comprising a series of sheet metal panels joined end to end and disposed longitudinally of a series of supports, a series of curved spring connectors disposed between said panels and supports, secondary buffers disposed within said spring connectors and in spaced relationship to a major portion of the inner walls thereof, clip means for slideably mounting said panels upon said spring connectors, and means for supporting said connectors upon said supports.

9. A highway guard rail comprising a series of sheet metal panels in end to end relationship disposed longitudinally of a series of supports, a series of curved spring connectors disposed between said panels and supports, secondary buffers disposed within said spring connectors in such a manner that an initial impact is first absorbed by said connectors before said secondary elements 25 become operative, means for mounting said panels upon said spring connectors, and means for supporting said connectors upon said supports.

10. A highway guard rail comprising a series of sheet metal panels in end to end relationship disposed longitudinally of a series of supports, a series of curved spring connectors disposed between said panels and supports, secondary buffers disposed within said spring connectors in such a manner that an initial impact is first absorbed by said connectors before said secondary elements 35 become operative, bolts and nuts uniting said panels with said spring connectors, and a bolt and nut for mounting said connectors upon each 40 respective support.

11. A highway guard rail comprising a series of metal panels joined end to end and disposed longitudinally of a series of supports, a series of annular spring connectors disposed between said panels and said supports, said connectors having their vertical axes disposed at substantially right angles to said panels; secondary buffer elements disposed within said spring connectors in spaced relationship to a portion of the interiors thereof, 50 means joining said metal panels to said spring connectors, and means for mounting said springs 55 and connectors upon said supports.

12. A highway guard rail comprising a series of metal panels joined end to end and disposed longitudinally of a series of supports, a series of circular spring connectors disposed between said panels and said supports, said connectors having their vertical axes disposed at substantially right angles to said panels; secondary buffer elements disposed within said spring connectors in spaced relationship to a portion of the interiors thereof, 60 means slideably mounting said metal panels upon said spring connectors, and means for attaching said connectors to said supports in 65 operative position.

13. A highway guard rail comprising a series of metal panels joined end to end and disposed longitudinally of a series of supports, a series of curved spring connectors disposed between 70

said panels and said supports, secondary buffer elements within said spring connectors and in spaced relationship to a portion of the inner walls thereof, means for mounting said panels upon 5 said connectors, and means for attaching said connectors to said supports in operative position.

14. A device of the character described comprising a support, a strip of metal disposed longitudinally thereto, and spring means for mounting said strip of metal upon said support, said means comprising separate cylindrical springs so positioned that one of said elements yields a predetermined degree under an impact before the other of said elements becomes operative and 10 likewise sets up a spring resistance tending to nullify said impact.

15. A device of the character described comprising a support, a strip of metal disposed longitudinally thereof, and spring means for mounting said strip of metal upon said support, said means comprising a series of annular springs so positioned that one of said elements yields a predetermined degree under an impact before the 15 next succeeding element in the series becomes operative and likewise sets up a spring resistance tending to nullify said impact.

16. A device of the character described comprising a series of supports, a sheet of metal disposed longitudinally and entirely to one side thereof, and a multiple buffer element disposed between said metal and said supports and uniting one with the other, said buffer having an outer portion calculated to absorb an initial shock, and 20 an inner portion which becomes operative upon said outer portion's having absorbed a certain impacting force.

17. A device of the character described comprising a series of supports, an impact member disposed longitudinally thereof, and a multiple buffer element disposed between said impact member and said supports and uniting one with the other, said buffer having an outer portion calculated to absorb an initial shock, and an inner 25 portion which becomes operative upon said outer portion's having absorbed a certain impacting force.

18. A highway guard including a plurality of posts, a metal rail extending past a plurality of said posts, tubular springs at the posts, and other springs at the posts extending beyond the tubular springs and positioning the rail normally out of 30 contact with the tubular springs.

19. A highway guard including a plurality of posts, a rail extending past a plurality of said posts, tubular springs at the posts, other springs at the posts supporting the rail normally out of 35 contact with the tubular springs, the said other

springs being resistant to light loads and yieldable under heavy loads applied lengthwise and transversely of the rail, the tubular springs being resistant to heavy loads applied lengthwise and transversely of the rail and transmitted to them 40 by the rail.

20. A highway guard including a plurality of posts, a rail extending past a plurality of said posts, tubular springs at the posts, other springs at the posts supporting the rail normally out of 45 contact with the tubular springs, the said other springs being resistant to light loads and yieldable under heavy loads applied lengthwise and transversely of the rail, the several springs at any post cooperating to resist heavy loads applied lengthwise as well as transversely of the rail.

21. A highway guard including a plurality of posts, a rail extending past a plurality of said posts, tubular springs at the posts, other springs at the posts supporting the rail normally out of 50 contact with the tubular springs, a rail tensioning spring anchored at the ends of said rail and resistant to light loads applied lengthwise of the rail, the several springs cooperating to resist heavy loads applied lengthwise as well as transversely of the rail.

22. A highway guard including a plurality of posts, a rail member extending past a plurality of said posts, anchor means at the ends of the 55 rail resistant to light loads applied lengthwise of the rail, tubular spring members mounted on the highway side of said posts, and other spring members normally supporting the rail out of contact with the tubular springs, the said other springs being resistant to light loads and yieldable under heavy loads.

23. A highway guard including a plurality of posts, a rail member extending past a plurality of said posts, rail supporting spring members mounted on said posts, and tubular spring members mounted on the posts between the rail and the posts and within the rail supporting springs and being normally out of contact with the rail.

24. A highway guard including a plurality of posts, a rail extending past a plurality of said posts, tubular springs at the posts, other springs at the posts supporting the rail normally out of contact with the tubular springs, the said other springs being resistant to light loads and yieldable under heavy loads applied lengthwise and transversely of the rail, the tubular springs being resistant to heavy loads applied lengthwise and transversely of the rail, and a rail tensioning spring positioned at the end of said rail and attached thereto.

EUGENE V. CAMP.
